US00D947800S

(12) **United States Design Patent** (10) **Patent No.:** **US D947,800 S**
Cook et al. (45) **Date of Patent:** **** Apr. 5, 2022**

(54) **INTEGRATED MODULE**

- (71) Applicant: **CACI, Inc.—Federal**, Arlington, VA (US)
- (72) Inventors: **James Andrew Cook**, Lompoc, CA (US); **Eric David Nystrom**, Goleta, CA (US); **Renato M. Camarda**, Fanwood, NJ (US)
- (73) Assignee: **CACI, Inc.—Federal**, Reston, VA (US)
- (**) Term: **15 Years**
- (21) Appl. No.: **29/701,214**
- (22) Filed: **Aug. 9, 2019**

Related U.S. Application Data

- (63) Continuation of application No. 16/512,713, filed on Jul. 16, 2019.
- (51) **LOC (13) Cl.** **13-03**
U.S. Cl.
USPC **D13/182**
- (58) **Field of Classification Search**
USPC **D13/182; 361/748, 752, 760, 761, 807, 361/808, 736, 719, 720; 174/250, 253, 174/255, 68.1; 363/144, 147**
